UNITED STATES PATENT OFFICE

172,851

CREAM PITCHER OR THE LIKE

John O. Van Koert, Newburyport, Mass., assignor
to Towle Manufacturing Company, Newbury-
port, Mass., a corporation of Massachusetts

Application May 12, 1953, Serial No. 24,982

Term of patent 14 years

(Cl. D44—21)

To all whom it may concern:

Be it known that I, John O. Van Koert, a citizen of the United States of America, residing at Newburyport, county of Essex, and Commonwealth of Massachusetts, have invented a new, original, and ornamental Design for a Cream Pitcher or the like, of which the following is a specification, reference being had to the accompanying drawing, forming a part thereof.

Fig. 1 is a front elevational view of a cream pitcher or the like, showing my new design;

Fig. 2 is a rear elevation thereof;

Fig. 3 is a side elevation thereof; and

Fig. 4 is a side perspective view thereof.

I claim:

The ornamental design for a cream pitcher or the like, substantially as shown.
